UNITED STATES PATENT OFFICE.

FREDERICK PASSMORE GUTELIUS, OF MONTREAL, QUEBEC, CANADA.

SMOKE-JACK FOR ENGINE-HOUSES.

No. 843,941.

Specification of Letters Patent.

Patented Feb. 12, 1907.

Application filed May 24, 1905. Serial No. 261,979.

To all whom it may concern:

Be it known that I, FREDERICK PASSMORE GUTELIUS, of the city of Montreal, Province of Quebec, Canada, have invented certain new and useful Improvements in Smoke-Jacks for Engine-Houses; and I hereby declare that the following is a full, clear, and exact description of the same.

My invention relates particularly to fire-proof smoke-jacks for railway engine-houses; and it has for its object to provide a jack of this type which will be more durable and lighter in weight and more easily constructed than smoke-jacks of this type heretofore known.

The invention may be said to consist of a smoke-jack for railway engine-houses composed of hardened plates or members made of finely-divided asbestos fiber (or the refuse or tailings of asbestos-mines) and a suitable filler or binding, such as hydraulic cement or the like, in a proper proportion to effectively bind the fibrous or comminuted asbestos together. The mass thus constituted is formed into plates and made hard by great pressure. These asbestos plates are supported or braced in the form of a smoke-jack by corner braces or posts, to which the plates are secured by rivets, nails, bolts, screws, or the like.

A further feature of the invention consists of a preferably adjustable auxiliary jack or hood made of the same hardened rigid asbestos plates secured together, preferably, by corner angle-irons, or corner asbestos members can be substituted for the angle-irons, or the longitudinal corner braces or posts of the main structure can be made of the rigid asbestos material.

For full comprehension, however, of my invention reference must be had to the accompanying drawings, forming a part of this specification, in which similar reference characters indicate the same parts; and wherein—

Figure 1 is a part side elevation and part longitudinal sectional view of a smoke-jack for railway engine-houses constructed according to my invention. Fig. 2 is a part plan view and part sectional view thereof. Fig. 3 is an enlarged horizontal sectional view of one corner of my improved jack. Figs. 4 and 5 are detail views of modified corner posts or braces. Fig. 6 is a side elevation, partly in vertical sectional view, of a circular jack constructed according to my invention.

Fig. 7 is a plan view thereof. Fig. 8 is a detail perspective view of one of the members thereof, and Fig. 9 is a detail perspective view of a modified manner of connecting together the arciform members of the tubular jack. Fig. 10 is an enlarged detail perspective view illustrating particularly the means for adjustably securing the auxiliary jack in the main jack.

The preferred construction of my improved smoke-jack for railway engine-houses consists of a series of hardened asbestos plates *b*, secured by nails *c* (or other preferred fastening devices—such as rivets, bolts, screws, or the like) to vertical supporting members consisting of, preferably, four angle-iron *d* posts, secured rigidly at their lower ends in the corners of a rectangular opening in the roof *e* of the engine-house, such asbestos plates being preferably of a width to extend completely across each side of the jack and vertically, in the case of comparatively low stacks, to within a short distance of the full height thereof, although it is sometimes found that plates of sufficient length to extend the full required height are not available. In such cases more than one plate to each side of the jack are used. These plates are formed of finely-divided asbestos fiber (or the refuse or tailings of asbestos-mines) and a suitable filler or binding, such as hydraulic cement or the like, in a proper proportion to effectively bind the fibrous or comminuted asbestos together. The mass thus constituted is pressed into plates of any required shape.

I construct the cowl-plate *g* of the stack also preferably of a single piece of the hardened asbestos plate and of concavo-convex formation with its convex side uppermost.

Circular jacks are constructed according to my invention by forming arciform plates *h* with flanged vertical edges *h'* of the above-described rigid asbestos material and securing them together by bolting (or otherwise fastening) the flanges of each to the flanges of the others contiguous thereto, or the arciform members can be made without flanges and secured together by straps *h*² of the same asbestos material, all as shown in Figs. 6, 7, 8, and 9.

In order to prevent leakage through the roof of the engine-house around the base of my smoke-jack, I locate a series of wood,

iron, or asbestos pieces *i* at the angle of junction of such parts and extend the roof-covering *k*, usually tar and gravel, over the said pieces *i* and a short distance up the sides of the jack, while an encircling band, of iron, asbestos, or wood planking *m*, is secured to the upper end of my improved asbestos plate-casing by a series of eyebolts *o*, which afford means whereby guy-wires *p* for bracing the jack are secured.

An adjustable auxiliary jack *r* is suspended in corner-brackets *s*, bolted to the lower end portions of the posts *d*, which project below the roof *e* to accommodate them. The construction of the auxiliary jack constitutes a feature of my invention. Such auxiliary jack consists of a throat portion and a flared mouth portion each formed of, preferably, four sides and each of the sides consisting of a hardened asbestos plate *t*. The side edges of each plate are secured to the side edges of the others at the corners of the throat and flared mouth by exterior angle-irons *v*, extending from the bottom of the flared mouth continuously to the top of the throat portion, thereby uniting the said throat and mouth in one piece with plane unbroken interior surface from bottom to top. As before mentioned, this auxiliary jack or hood is adjustable, the purpose being to enable it to be adjusted to and set in different positions relatively to the rails in the engine-house, and to prevent this hood accidentally falling out of the jack proper I utilize an eyebolt *2* as a part of the means for securing the lower end of one of the posts in place and connect such eyebolt by a safety-chain *3* to an eyebolt *4* upon the hood. The hood is adjusted by removing bolts *10*, shifting the hood and with it brackets *s* upwardly or downwardly into registering position with other holes of the series *12*, and then again inserting the bolts.

The posts, if of wood or iron work, are given a thick coat of fireproof paint, preferably 45 "asbestos" cold-water paint.

Under certain conditions I prefer to construct the vertical supporting members of one-quarter round or three-quarters round posts (see Figs. 4 and 5) made of the above-described rigid asbestos material; but usually angle-irons, as shown in Figs. 1, 2, and 3, are found preferable.

The great advantage of railway engine-house smoke-jacks constructed according to the foregoing is that besides being fireproof and acting as ventilators they present smooth unbroken interiors, thus preventing the inflammable particles which come in contact therewith adhering thereto and obviating the condensation of the steam and the gases of combustion which pass upwardly therethrough and come in contact therewith. A further and important advantage over other jacks is simplicity of construction and minimum weight.

What I claim is as follows:

1. A smoke-jack for a railway engine-house comprising supporting - posts and hardened rigid asbestos plates secured thereto.

2. The combination with the roof of a railway engine-house having an opening therein, of a smoke-jack consisting of a series of vertical supporting members, a series of hardened rigid asbestos plates secured at their side edges to the supporting members and extending from the roof to within a short distance of the top of such members, a hardened rigid asbestos cowl-plate supported by and extending over the space between the supporting members, and means for bracing the jack thus constructed, substantially as described and for the purpose set forth.

3. The combination with the roof of a railway engine-house having a rectangular opening therein, of a ventilating smoke-jack consisting of four posts secured rigidly in the corners of such opening, a series of hardened rigid asbestos plates secured at their side edges to the posts and forming the sides of the jack, such plates extending from the roof to within a short distance of the top of the posts, a cowl-plate supported by the tops of the posts and consisting of a hardened rigid asbestos plate, an auxiliary jack or hood comprising a throat portion and a flared mouth 95 portion and consisting of a series of rigid asbestos plates, and connecting members securing the same together, means for bracing the main stack thus constructed, and means adjustably supporting such auxiliary jack or hood in the lower end of the main jack, substantially as described and for the purpose set forth.

4. The combination with the roof of a railway engine-house having a rectangular opening therein, of a ventilating smoke-jack consisting of four angle-iron posts secured rigidly in the corners of such opening, a series of hardened asbestos plates secured at their side edges to the posts and forming the sides 110 of the jack, such plates extending from the roof to within a short distance of the top of the posts, a cowl-plate supported by the tops of the posts and consisting of a hardened asbestos plate, an auxiliary jack or hood comprising a throat portion and a flared mouth 115 portion and consisting of a series of asbestos plates and connecting members securing the same together means for bracing the main stack thus constructed, and means slidably supporting such auxiliary jack or hood in the lower end of the main jack, substantially as described and for the purpose set forth.

5. The combination with the roof of a railway engine-house having a rectangular opening therein, of a ventilating smoke-jack consisting of four posts secured rigidly in the corners of such opening, a series of hardened asbestos plates secured at their side edges to the posts and forming the sides of the jack, 130

such plates extending from the roof to within a short distance of the top of the posts, a cowl-plate supported by the tops of the posts and consisting of a hardened asbestos plate, 5 an auxiliary jack or hood comprising a throat portion and a flared mouth portion and consisting of a series of asbestos plates and 10 consisting of a series of asbestos plates and connecting members securing the same together, means for bracing the main jack thus 15 constructed, and means adjustably supporting such auxiliary jack or hood in the lower end of the main jack, packing-strips extending along the line of juncture of the main jack with the roof, and roofing material extending over such strips and partially up the 20 sides of the said main jack, substantially as described and for the purpose set forth.

6. The combination with the roof of a railway engine-house having a rectangular opening therein, of a ventilating smoke-jack consisting of angle-iron posts secured rigidly in corners of such opening and extending vertically from a short distance below the roof, 25 a series of hardened asbestos plates secured at their side edges to the inside faces of the posts and forming the sides of the jack, such plates extending from the roof to within a short distance of the top of the posts, a con-

cavo-convex cowl-plate supported by the tops of the posts with its convex side uppermost and consisting of a hardened asbestos plate, an auxiliary jack or hood comprising a throat portion and a flared mouth portion and consisting of a series of asbestos plates and 30 a series of angle-irons extending along the exterior of the corners formed by the abutting edges of such plates and from the bottom of the mouth portion to the top of the throat portion and securing the same together, means for bracing the main jack thus 35 constructed, a series of brackets secured to the lower portions of the posts and adjustably supporting such auxiliary jack or hood in the lower end of the main jack, and a safety-chain connected at one end to a stationary part of the structure and at its other end to the auxiliary jack or hood, substantially as described and for the purpose set forth.

In testimony whereof I have signed my 40 name to this specification in the presence of two subscribing witnesses.

FREDERICK PASSMORE GUTELIUS.
